DEAD END CLAMP FOR CABLES

Maxwell E. Noyes, Mount Lebanon, Pa., assignor
to Aluminum Company of America, Pittsburgh,
Pa., a corporation of Pennsylvania

Application April 19, 1930. Serial No. 445,581

6 Claims. (Cl. 24—135)

This invention relates to strain clamps for steel reinforced aluminum cables and more particularly relates to improvements in the details of construction of such devices to the general end that 5 simplicity may be obtained with attendant low cost.

A further object of the present invention resides in the provision of a strain clamp provided with an accelerating curved and grooved notch for receiving and snubbing the cable, which accelerating curve is co-planar with the reach of the cable whereby compactness and simplicity of construction may be obtained while still maintaining desired snubbing action upon the cable.

15 A further object of the present invention resides in the provision of a strain clamp having grooved portions provided with an accelerating curve for receiving and snubbing the cable and which clamp also has a gripping means disposed 20 beyond the accelerating curved notch and disposed in alignment therewith whereby secure snubbing and clamping may be obtained by the device and with a compact disposition of the parts.

25 Further and other objects of the present invention will be hereinafter set forth in the accompanying specification and claims and shown in the drawings, which by way of illustration show what I now consider to be a preferred embodiment of the invention.

In the drawings:

Figure 1 shows a pair of strain clamps associated with supporting insulators;

Fig. 2 is an enlarged side view shown partly in section of one of the improved strain clamps;

Fig. 3 shows a detail sectional view of the clamping or cable securing means; this section is taken on line 3—3 of Fig. 2;

Fig. 4 is a top plan view of the part shown in Fig. 2, the view being taken along the line 4—4 of Fig. 2 and looking in the direction of the arrows;

Fig. 5 is an end view taken from the right on Fig. 2 substantially along line 5—5 and looking in the direction of the arrows;

Fig. 6 is a side view of the gripping device, the view being taken substantially along line 6—6 and looking in the direction of the arrows;

Figs. 7, 8 and 9 are sections through the 50 notched portion of the clamp, the sections being taken substantially on lines 7—7, 8—8 and 9—9 of Fig. 2;

Fig. 10 is a view similar to Fig. 2 of a modified form of clamp in which a different form of gripping element is provided;

Fig. 11 is a detail sectional view taken on line 11—11 of Fig. 10; and

Fig. 12 is a view of certain parts shown in Fig. 10, which shows the relation of the gripping elements with respect to the U bolt before assembly 60 is complete.

In more detail referring to Fig. 1, 10 represent supporting insulators. The strain relieving cable securing devices generally designated 11, are suitably pivotally connected to the insulators 65 by pivot bolts 12 and each strain relieving device comprises a light weight casting having a pair of spaced arm portions 13 (see Fig. 4) and an intermediate notched cable receiving portion 14. This notched portion 14 is disposed co-planar with the reach of the cable 15 and the notch is symmetrical with respect to a median plane 16 (Fig. 4). The shape of the cross section of the curved notch at various points is shown in Figs. 7, 8 and 9. As best shown in 75 Fig. 2, the cable receiving notched portion 14 is shaped with an accelerating curve 17. This curve is not a true circle but is of large radius where the cable enters the clamp where the tension is maximum and thereafter gradually decreases in radius, thus effecting an increased snubbing action as the tension in the cable falls off. Thus the notched cable receiving portion or groove 14 extends rearwardly from the point of entry of the taut portion or reach of the cable 80 toward the point of attachment of the strain clamp at 12, and forwardly away from the point of attachment toward the point of cooperation of the cable with the clamping member 19 in the portion 18 of the groove and toward the 85 point of exit adjacent the slack portion of the cable. The curvature of the groove is greatest at points remote from the point of entrance of the taut portion or reach of the cable into the groove 14. From the intermediate point (near 90 the section line 9—9, Fig. 2) in the strain clamp which is closest to the point of attachment at 12, the groove 14 extends forwardly to the point of entrance of the reach of the cable and forwardly to the point of cooperation with the 95 clamping member 19. The curvature of the groove decreases from the intermediate point towards the point of entrance of the reach of the cable and the curvature of the groove increases from the intermediate point toward the 100 clamping point and toward the point of exit of the slack portion of the cable. By providing the notched or grooved portion with the accelerating curve and disposing it co-planar with the reach of the cable and locating the curved notch 105 110

symmetrical with respect to the median plane 16 an extremely compact construction is provided and one in which the desired snubbing action on the cable may be secured. Another 5 advantage resulting from the disposition of the curved notch or groove 14 entirely symmetrically with respect to the median plane 16 which intersects the center of the groove (the groove being wholly co-planar with the reach of the 10 cable) is that turning moment does not occur at the point of attachment when strain is applied to the cable.

Cable gripping and clamping devices

15 At the end of the accelerating curve 17 and groove 14, where the radius of the curve 17 is the least, the cable receiving member is extended and provided with a reverse curved notched portion, generally designated 18 in Fig. 2. The 20 groove of this reversely curved notched portion is substantially in alignment with the groove 14. The cable is gripped with respect to the reverse curved and grooved portion 18 by means of a gripping or clamping element 19 which has 25 proper curvature to secure the desired gripping action of the cable upon the reverse curved notched portion of the cable receiving member. The gripping element 19 is provided with an aperture 20 therethrough adapted to receive a 30 U bolt 21. This U bolt in turn passes through openings in extended portions of the casting to the sides of the reverse curved notched portion 18 and is suitably secured by means such as nuts 22 (see Fig. 3).

35 According to the modification shown in Fig. 10, two reverse curved gripping notches 18a and 18b are provided in lieu of one and the gripping elements 19a and 19b are arranged to clamp the cable tightly against these reverse curved 40 notched portions. In lieu of providing an aperture through members 19a and 19b to receive the fastening U bolts 21, the elements 19a and 19b are initially formed with open tongue or clamp 45 portions 23 (see Fig. 12) which are afterwards peened over as indicated at 23b (see Fig. 10).

I claim:

1. A strain clamp for a cable comprising a strain relieving member provided with a grooved portion which is shaped with an accelerating 50 curve, said groove from end to end being entirely co-planar with the reach of the cable which is received in and snubbed by the accelerating curved groove of the strain relieving member and a clamping member directly clamping the cable 55 in the groove of the strain relieving member in a direction normal to the bottom of the groove, the aforesaid accelerating curved portion of the groove having one portion extending rearwardly from the point of entry of the reach of the cable 60 toward the point of attachment of the strain clamp and another portion extending forwardly away from the said point of attachment toward the point of cooperation of the cable with the clamping member and the point of exit of the 65 cable.

2. A strain clamp for a cable comprising a strain relieving member provided with a grooved cable receiving portion shaped with an accelerating curvature which is greatest at points remote 70 from the point of entrance of the reach of the cable into the groove to provide progressively increasing snubbing action, said groove being from end to end entirely co-planar with the reach of the cable whereby twisting strains upon the 75 strain relieving member are minimized and where-

by turning moment does not occur at the point of attachment of the strain relieving member when strain is applied to the cable, and a clamping member clamping the cable directly against the bottom of the groove and in a direction normal thereto, said clamping member and the groove adjacent thereto providing for reversed curvature of the cable and increased snubbing action of the cable in the groove adjacent the clamp with the cable free in the groove throughout the length of the latter up to said clamping member, said strain relieving member having its accelerating curved groove shaped and disposed so that the cable extends forwardly from an intermediate point adjacent the point of attachment of the strain relieving member to the point of entrance of the reach of the cable and so that the cable also extends forwardly from the said intermediate point to the point of cooperation with the clamp. 80 85 90 95

3. A clamping and strain relieving device for a cable, said device comprising a member with a snubbing groove for receiving a cable, and clamping means cooperating with the cable for clamping the cable toward the bottom of the 100 snubbing groove, said snubbing groove leading the cable from its reach successively toward and then away from the point of attachment of the device, said snubbing groove throughout its length being entirely co-planar with the reach of the 105 cable and with progressively diminishing curvature from the point of maximum snubbing adjacent the clamp to the point of entrance of the reach of the cable, said clamping means cooperating with the cable in such groove in such direction 110 that the effect of clamping and the stress of the taut reach of the cable both cooperate to force the cable to the bottom of the groove to provide progressively increased snubbing action of the cable in the groove while minimizing twisting strains upon the member and obviating torsional strains at the point of attachment of the device and strains upon the cable transversely of the groove. 115 120

4. A strain clamp for a cable including a strain relieving device having a clamping portion and constructed for progressively increased direct snubbing action both against the cable and only in the plane of the reach of the cable, from its point of entry to and through the clamping portion, said device including a snubbing groove entirely co-planar with the reach of the cable and extending from the point of entry of the cable rearwardly toward the point of attachment of the device and then forwardly away from said point to the aforesaid clamping portion and having a progressively decreasing radius of curvature throughout its said extent, and the clamping portion of said device including a clamping member constructed for clamping action against the cable in a direction normal to the bottom of the groove and with the cable co-planar with its reach. 125 130 135

5. A strain clamp for a cable comprising a strain relieving member in which is formed a groove of increasing curvature, said groove extending rearwardly from the point of entry of the taut portion of the cable toward the point of attachment of said strain clamp and forwardly away from said point of attachment toward the point of exit adjacent the slack portion of the cable, said groove being wholly co-planar with the reach of the cable which extends thereinto so that turning moment does not occur at the 140 145 150

point of attachment when strain is applied to the cable.

6. A strain clamp for a cable comprising a strain relieving member in which is formed a groove of increasing curvature, said groove extending rearwardly from the point of entry of the taut portion of the cable and having increasing curvature towards the point of attachment of said strain clamp, and said groove extending

forwardly toward the point of exit adjacent the slack portion of the cable with increasing curvature away from said point of attachment of the strain clamp, said groove being disposed entirely symmetrically with respect to a median plane which intersects the center of the groove so that turning moment does not occur at the point of attachment when strain is applied to the cable.
